US0D1051959S

(12) **United States Design Patent** (10) Patent No.: **US D1,051,959 S**
(45) Date of Patent: ** Nov. 19, 2024

(54) **AGITATOR**

(71) Applicant: **WHIRLPOOL CORPORATION**,
Benton Harbor, MI (US)

(72) Inventors: **Jonathan A. Andrejczuk**, Stevensville,
MI (US); **Benjamin D. Lowell**, Benton
Harbor, MI (US); **Eric W. Merrow**,
Benton Harbor, MI (US); **Sayer J.
Murphy**, St. Joseph, MI (US)

(73) Assignee: **WHIRLPOOL CORPORATION**,
Benton Harbor, MI (US)

(**) Term: **15 Years**

(21) Appl. No.: **29/756,319**

(22) Filed: **Oct. 27, 2020**

(51) LOC (14) Cl. **15-05**

(52) U.S. Cl.

USPC **D32/26**

(58) **Field of Classification Search**

(57) **CLAIM**

The ornamental design for an agitator as shown and described.

DESCRIPTION

FIG. 1 is a perspective view of an agitator for use in conjunction with a laundry machine;

FIG. 2 is a front side view of the agitator of FIG. 1;

FIG. 3 is a back side view of the agitator of FIG. 1;

FIG. 4 is a left side view of the agitator of FIG. 1;

FIG. 5 is a right side view of the agitator of FIG. 1;

FIG. 6 is a top side view of the agitator of FIG. 1; and,

FIG. 7 is a bottom view of the agitator of FIG. 1.

The broken lines depict portions of the agitator that form no part of the claimed design. The dot dash broken lines depict the bounds of the claim which form no part of the claimed design.

1 Claim, 7 Drawing Sheets
